(57) **CLAIM**

We claim the ornamental design for a video communication device, as shown and described.

DESCRIPTION

FIG. 1 is front elevation view of the video communication device showing my new design;

FIG. 2 is a top plan view thereof;

FIG. 3 is a rear elevation view thereof;

FIG. 4 is a left side elevation view thereof;

FIG. 5 is a right side elevation view thereof;

FIG. 6 is a bottom plan view thereof; and,

FIG. 7 is a top perspective view thereof.
